CLAIM

The ornamental design for a nasal ice pack, as shown and described.

DESCRIPTION

FIG. 1 is a rear view of a nasal ice pack of our design; FIG. 2 is a front view thereof; FIG. 3 is a bottom view thereof; FIG. 4 is a top view thereof; FIG. 5 is a side view thereof; and, FIG. 6 is a front view of the nasal ice pack of our invention. The broken line showing of human form is included for the purpose of illustrating environmental structure and forms no part of the claimed design.
